UNITED STATES PATENT OFFICE.

BURTON W. SWEET, OF CLEVELAND, OHIO, ASSIGNOR TO HARRY Z. SANDS, OF CLEVELAND, OHIO.

SHEET-METAL SUPPORTING-ARM.

941,591.

Specification of Letters Patent. Patented Nov. 30, 1909.

Application filed March 18, 1907. Serial No. 362,874.

To all whom it may concern:

Be it known that I, BURTON W. SWEET, a citizen of the United States of America, and a resident of Cleveland, in the county of 5 Cuyahoga and State of Ohio, have invented certain new and useful Improvements in Sheet-Metal Supporting-Arms, of which the following is a specification.

My invention relates to improvements in 10 supporting arms for telephones, and has for its object the construction of a pivoted arm, which shall be readily formed from strap or sheet metal, while insuring the maximum rigidity and economy in cost of construction. 15 Devices of this general type now upon the market, commonly are formed of pivoted castings, or tubular members united by pivots, but these are heavier, more unwieldy, and liable to breakage than is the device of 20 my invention hereinafter described.

The particular features will be more fully explained in connection with the accompanying drawings, but I may state, in a preliminary way, that the device consists essentially 25 of strap metal arms pivoted together and carried at one end by a sheet metal bracket, while at the outer end of said pivoted arms, is carried a suitable telephone supporting member, likewise formed of sheet metal. 30 The stampings and punchings are easily and cheaply made, while the pivot-parts preferably are turned out in quantities by automatic screw machines, or are cut from metal rods, and sheet metal parts are reinforced 35 simply by riveting them together, thus providing a strong, presentable, and yet very cheap article. Moreover, the dies necessary for stamping out and forming these parts, are few in number and by no means 40 expensive.

The drawings, forming a portion of this specification, comprise:—

Figure I, which is a view of the entire device in side elevation. Fig. II is a plan view of the same. Fig. III is a plan view of one of the punchings for a telephone support. Figs. IV and V are side views respectively of the extensible hook and brace for said support. Fig. VI is a detail showing 45 one of the pivot-joints. Fig. VII is a plan view of a washer. Fig. VIII is a detail in partial perspective and partially broken away, showing the bracket-mounting. Fig. 50 IX is a similar detail showing the pivot-mounting for the telephone support. Fig. 55

X is another detail in longitudinal section illustrating the adjustable hook of the support, and Fig. XI is a detail in side elevation, showing the combined washer and cord-retaining loop.

Throughout each of the several figures of the drawings, I have indicated similar parts by the same character of reference.

A simple two-section supporting arm is shown in Figs. I and II, which embodies the 60 details of my invention, although three or more sections may readily be used, and provision may be made for supporting a plurality of telephone instruments upon a single bracket. I shall explain, however, the 65 simple form herein illustrated. The bracket *b* is formed from an integral sheet metal stamping having a punched attaching shield *b'*, the riveted web *b*² and an outer tubular socket *b*³, all as best shown in Fig. VIII. A 70 solid pivot post *a* is mounted in the tubular socket and carries the inner pivoted arm *c* from its upper end. The sides of said pivot post are sheared off as at *a'*, above and below, so as to receive the washer *a*² (see Figs. 75 VI and VII), beyond which are provided screws *a*³, entering tapped openings formed in either end of said pivot post. Similar 80 pivotal mountings are provided at each of the joints of the supporting arm. Two separate sections *c* *d* are shown for said arm; each being formed from strap metal doubled 85 at one end to form a terminal tubular socket, as *c'*, riveted together throughout the body portion, and shaped over a mandrel near 90 its other end to provide a second tubular socket, as *c*². Obviously two symmetrical strap-metal members may be used, but I prefer the one herein shown. For manufacturing 95 said arms, I have most successfully employed cold-rolled key-stock of suitable width and gage, which may be readily worked in this manner, and affords the necessary rigidity for a device of this class. A double pivot mounting *e* unites the parts, 100 while the terminal pivot *f* serves to carry the telephone support. Each of these pivot 105 mountings has an intermediate shoulder, as *e'* *f'*, which may either be integral with the pivot post, or may be formed by an interposed washer.

In the precise structure shown, this telephone support is one adapted to receive the base of an ordinary desk-set, and is provided with three co-acting hooked members, adapt- 110

ed to engage and hold said base. Two of said members, together with the pivot-socket, are formed from the sheet metal blank shown in Fig. III, wherein the hooks g are provided upon the divergent arms g' , and are rigidly secured together by the transverse brace g^2 (see also Fig. V). The intermediate pivot socket g^3 , and the integral tapped screw socket g^4 , are formed from the interior portions of the blank. An adjustable hook h , mounted at the end above a tubular portion, is attached to the top of the telephone support by means of a long adjusting screw i , which is adapted to permit the adjustment of said hook h , and secure or release the base of the desk set. The intermediate washer j has a downwardly extending lug j' and a loop j^2 , wherein the conducting cord for the telephone is adapted to be held; (see Fig. XI).

From the foregoing it will be appreciated that the pivoted supporting arm not only is strong and serviceable, but that it is cheaply constructed, and when suitably plated, enameled, or otherwise provided with a durable and ornamental finish, the article is extremely salable.

The removable telephone support permits the instrument to be taken up for more convenient use, while normally holding it in convenient position ready to be turned upon its pivotal mountings to any extent permitted by the length of the supporting arm. The cord loop prevents the conducting cord from being caught in the bracket when the arms thereof are swung back and forth. These arms are extremely rigid throughout their riveted body portions, while affording integral socket members for the pivot posts, and the telephone support is so shaped and braced, as to present the rigidity of a cast metal article, without its undesirable weight. By employing sheared pivot posts and special washers, well shown in Figs. VI and VIII, the pivotal mountings of my improved arm are not loosened by continued use.

Having now described the device of my invention, I claim as new, and desire to secure by Letters Patent, the following:

1. In a telephone support, the combination with an integral sheet metal member, bent to afford two engaging ears, a pivotal socket and a tapped abutment, of an adjust-

able hook and an adjusting screw associated therewith engaging the tapped abutment, substantially as set forth. 55

2. In a telephone support, the combination with an integral sheet metal member, comprising two diverging arms terminating in retaining hooks, an intermediate socket member, and a reinforced tapped abutment, of a brace rigidly uniting said arms, an adjustable hook, and an adjusting screw, engaging said hook and entering the tapped abutment, substantially as set forth. 60 65

3. In a device of the class described, the combination with pivoted arm-sections, of an integral washer and cord support positioned adjacent to the pivotal mounting; said washer affording retaining means for the pivoted sections and being provided with an opening for the conducting cord, whereby the latter is retained in place with respect to the arm, substantially as set forth. 70

4. In a telephone supporting arm, the combination with an attaching bracket, of a plurality of pivoted sections, forming an extensible arm; each of said sections comprising a strap metal member doubled upon itself to afford terminal sockets and a reinforced body portion riveted together, and a sheet metal telephone support carried at the outer end of said arm, comprising divergent hooked arms, an integral socket, and an opposing adjustable hook, substantially as set forth. 75 80 85

5. In a telephone supporting arm, the combination with a plurality of pivoted arm sections; each formed of strap metal doubled upon itself to afford terminal socket members, and a reinforced body portion, pivot posts uniting and attaching said sections, a sheet metal bracket pivotally carrying the inner end of said arm, and a sheet metal telephone support, comprising divergent hooked arms an integral socket, an opposing hook, and an adjusting screw therefor, substantially as set forth. 90 95

Signed at Cleveland, this 8th day of March, A. D. 1907, in the presence of the 100 undersigned witnesses.

BURTON W. SWEET.
